COMBINATION CURTAIN, DRAPE, AND SHADE HOLDER

Arrie Barbee, Pontiac, Mich.

Application December 17, 1943, Serial No. 514,681

4 Claims. (Cl. 248—254)

This invention relates to brackets used in supporting panel curtains, drapes and a shade, and has as its object the provision of a pair of brackets which may be readily mounted upon the surface of a window casing and which are equipped for supporting therebetween a window shade, curtains and drapes.

The invention together with its objects and advantages will be best understood from a study of the following description taken in connection with the accompanying drawings wherein:

Figure 1 is a top plan view illustrating the invention.

Figure 2 is a sectional view taken substantially on a line 2—2 of Figure 1.

Figure 3 is a front elevational view of one of the brackets.

Figure 4 is a perspective view of one of the detachable brackets for the curtain and drape rods.

Figure 5 is a fragmentary elevational view of the sliding connection between the sections of the curtain and drape rods, and

Figure 6 is a fragmentary view in elevation of the end of one of the curtain rods.

In accordance with the present invention it will be seen that there are provided two bracket assemblies 5 and 6 respectively.

One of the bracket assemblies is provided for attachment to the window casing at the left hand side thereof while the other of the assemblies is provided for attachment to the casing at the right hand side thereof.

Since the assemblies are substantially identical, a detailed description of one will teach the other.

Thus it will be seen that each assembly comprises a shade roller bracket 7 that is provided at one edge with an attaching flange 8 that is apertured to accommodate fastening elements 9 through the medium of which the bracket is attached to the surface of the window casing.

At the upper edge thereof the bracket 7 is provided with a lateral flange 10 that merges into an upstanding arm 11.

A substantially U-shaped curtain rod bracket 12 is provided and the same has one arm 13 thereof adapted to be disposed against one side of the bracket arm 11 while the other arm 14 of the bracket 12 is disposed in spaced parallelism to the arm 11 and is provided in its upper edge with a diagonal slot 15 for a purpose hereinafter more fully referred to. The web of the bracket member 12 is provided with an opening 16 to accommodate a fastening element 16a through the

medium of which the bracket 12 is secured to the window casing as shown in Figure 1.

A second curtain rod bracket 17 is provided and the same is substantially identical with the bracket 12 except that it is about one-half the size of the bracket 12 and is adapted to fit within the bracket 12 at one end of the latter as clearly shown in Figures 1 and 4.

The bracket 17 has an arm 18 thereof that is disposed in facial contact with the arm 11 at the side of the latter opposite to the arm 13 and arms 13 and 18 are secured to the arm 11 through the medium of bolts or rivets 19, arms 11, 13 and 18 being provided with registering openings to accommodate the bolts 19 as shown.

The other arm 20 of bracket 17 is disposed intermediate arms 11 and 14 and is provided in its upper edge with a diagonal, inclined slot 21 as shown.

20 The upper edges of the arms 13 and 18 are connected by a web portion 22.

A pair of sectional curtain and drape rods 23 and 24 of channel shape in cross section, are provided at their ends with a channel shaped 25 adapter 25 adapted to receive the arms 14 and 20, the adaptors having pins 26 and 26', respectively, disposed transversely thereof and the pins are received in the slots 15 and 21, respectively, of the arms 14 and 20 to retain the rods in position on said arms.

In actual practice the brackets 7 will support therebetween a shade roller, the bracket 7 of the assembly 6 being provided with an aperture or eye to receive the pintles on one end of the

35 shade roller while the bracket 7 of the assembly 5 will be provided with a slot 28 to receive the squared pintle on the opposite end of the shade roller, the slot 28 having an inwardly projecting shoulder 29 to overlie the pintle and prevent 40 accidental removal thereof. Also the arms 14 of the brackets 12 will support therebetween a rod 24 from which may be suspended a valance or drape while the arms 20 of brackets 17 will serve to support therebetween a rod 23 identical

45 with the rod 24 and used for suspending or supporting a panel curtain.

It is thought that a clear understanding of the construction, utility and advantages of an invention of this character will be had without a more detailed description.

Having thus described the invention what is claimed as new is:

1. In a device of the class described, a bracket assembly including a bracket member having at one edge thereof an apertured attaching flange

and also having at its upper edge a laterally extending flange merging into a vertically disposed arm, a substantially U-shaped bracket having an arm contacting the first-named arm at one side of the latter and a second arm in parallelism to the first-named arm and provided to be engaged by one end of a curtain rod, and a second substantially U-shaped bracket shorter than the first-named U-shaped bracket and having an arm engaging the first-named arm at the side thereof opposite to the first-mentioned arm of the first U-shaped bracket and a second arm spaced inwardly from the second-named arm of the first U-shaped bracket and provided for the engagement therewith of one end of a drape rod, and a web connecting the facially contacting arms of said brackets and securing said arms together.

2. A curtain rod having each end formed with a channel member open along its upper edge, each of said channel members being adapted to receive in the channel thereof an arm of a supporting bracket, said arm having a notch in its upper edge, and a pin bridging the space between the sides of said channel member and engageable in the notch of said arm for detachably supporting said channel members on said arm.

3. In a bracket assembly of the character described, a shade roller bracket provided at one vertical edge with means for mounting the bracket

5 et on the surface of a window casing, and provided at its upper edge with a lateral flange merging into an upstanding arm, and a pair of U-shaped bracket members each having one arm thereof secured to each other and adapted for supporting on the first-named arm and a second arm spaced from the first-named arm, the second named arms of the brackets of said pair being laterally spaced from one another and each being adapted to have one end of a curtain rod engaged therewith.

10 4. In a bracket assembly of the character described, a shade roller bracket provided at one vertical edge with means for mounting the bracket on the surface of a window casing and provided at its upper edge with an offset forming an upstanding arm and a pair of U-shaped bracket members each having spaced apart arms, a pair of said arms being connected at their upper edges and adapted for supporting on the upper edge 15 of said upstanding arm, each of said remaining arms of the U-shaped bracket members being provided with an inclined slot extending downwardly from their upper edges and adapted to receive the ends of channel-shaped curtain rods having transverse pins seated in the slots of said last-named arms for supporting said rods on said last-named arms.

ARRIE BARBEE.
